UNITED STATES PATENT OFFICE

WILLIAM MONROE HUFFMAN, OF KENTENIA, KENTUCKY

MATERIAL EXCAVATING AND CONVEYING MACHINE

Application filed April 10, 1929. Serial No. 354,051.

This invention relates to an improved apparatus or machine for excavating material and dumping it onto a conveyor to be carried to a suitable source of deposit.

5 In carrying the invention into effect I have evolved and produced a novel structural organization of parts combined into a complete structure which is especially but not necessarily adapted for association with a 10 loading apparatus of the Jeffrey pit car loader type.

The gist of the invention is a novel mole head and burrowing device which is attached to the loading end of an endless conveyor such 15 as is used on a pit car loader of the aforesaid Jeffrey type.

The improved device is characteristic in form and distinguishable in the art in that it includes a relatively stationary burrowing 20 apron attached to the loading end of the endless conveyor and adapted to be forced beneath the material being acted on, together with a complementary and cooperative mole head for excavating, accumulating and 25 loading the loosened material onto the loading end of the conveyor.

These specific details and their relative arrangement and association will become more readily apparent from the following 30 description and drawings.

In the drawings:

Figure 1 is a fragmentary top plan view showing the loading end of a conveyor equipped with the improved excavating and 35 loading device as constructed in accordance with the present invention.

Figure 2 is a side elevational view of the structure seen in Figure 1.

Figure 3 is an enlarged fragmentary top 40 plan view with portions broken away and shown in sections disclosing the particular construction and arrangement of the excavating and loading device.

Figure 4 is a sectional view taken approximately 45 upon the plane of the line 4-4 of Figure 3.

Figure 5 is a central sectional view taken upon the plane of the line 5-5 of Figure 3.

Figure 6 is an enlarged detailed view on 50 the line 6-6 of Figure 3.

The complete structure may be well seen in Figure 3 wherein it will be observed that the reference character 7 designates generally the frame of the conveyor which in practice is associated with a wheel supported car body 55 of the pit loader type already referred to, the details of the loading car constituting no part of the invention. Associated with this frame is an endless conveyor 8 including a belt or the like 9 with cross retaining cleats 60 10. As seen in Figure 5 the belt is trained over a suitable pulley 11. Also as seen in Figure 5 the reference character 12 designates a part which may be conveniently designated as an apron, and excavating plate. 65 The inner end portion 13 is attached to the frame of the conveyor in any suitable manner and the projecting portion is bowed forwardly and downwardly and terminates in a beveled undercutting edge 14. At longitudinally spaced points this apron is provided with transverse slots 15. Cooperable with and relatively movable with respect to this apron is a mole head generally designated by the reference character 16 and comprising a body of general right angular configuration. It includes a body portion 17 carrying a toothed cutter bar 18 which rides on the apron 14. In addition it includes a right angular flanged portion 19 providing a shoulder behind which the material accumulates during the reciprocatory motion of the mole head 16 from the full line position to the dotted line position shown in Figure 4. 70

This mole head carries longitudinally bowed cover plates in the form of right angular brackets 20 which cover the slots 15 when the head is moved forward or to the undercutting and excavating position seen in dotted lines in Figure 4. This mole head is provided at its opposite ends with attaching brackets 21 carrying antifriction rollers 22 engaging the under side of the apron. The brackets are so designed as to permit pivotal connection at 23 with the reciprocatory operating rod 24. These rods are enclosed in a housing or casing 25 as seen in Figure 2 and extend rearwardly and connect with crank arms 26 on the operating shaft. The operating shaft is equipped with a sprocket 27 over which 75 80 85 90 95 100

a sprocket chain 28 is trained. Thus reciprocatory motion is imparted to the mole head at opposite sides of the conveyor frame in an obvious manner permitting the mole head to move back and forth beneath the hill of material as indicated in dotted lines by the reference character 29 in Figure 4.

In operation it is understood that the conveyor and its carrying frame are mounted upon the usual wheeled pit loading car which travels on a track in a manner not shown. This car is moved toward and against the load 29 of the material to be acted upon. Thus the cutting end 14 of the apron 12 is forced beneath the material and the mole head 16 is reciprocated back and forth. On the forward stroke it digs in, and on the return stroke it drags the loosened material back over the apron and onto the loading end 20 of the conveyor 8. The result is that the material is carried upwardly and enters into a car or other suitable source of deposit. The gist of the idea is in the continuous movement of the cutting end 14 of the apron 12 against the load of material and the relative reciprocatory motion of the mole head which excavates and loads.

From the foregoing description and drawings it will be seen that I have evolved and produced a simple, inexpensive, and practicable structure which will fulfill the requirements of an apparatus of this class in a highly satisfactory manner. It is thought too that persons skilled in the art to which the invention relates will be able to obtain a clear understanding of the same after considering the description in conjunction with the drawings, therefore, a more lengthy description is regarded unnecessary.

Having thus described the invention, what I claim as new and desire to secure by Letters Patent is:—

1. As a new product of manufacture, an attachment for the loading end of a conveyor frame of the class described comprising a longitudinally extending curved apron adapted to be fixedly mounted on the frame, said apron being provided adjacent its opposite ends with longitudinally elongated guide slots, and having its working edge formed into a cutting edge to burrow beneath the material being acted on, and a mole head slidably mounted for transverse reciprocation on said apron and including operating brackets extending through said slots, together with operating means connected with said brackets.

2. An attachment for the loading end of a conveyor frame of the class described comprising a longitudinally elongated curved plate functioning as a guiding and excavating apron, said plate adapted to be fixedly mounted on the loading end of said frame and being provided with a cutting edge and adjacent its opposite end with longitudinally elongated guide slots, a mole head mounted

for reciprocation on said plates and comprising a substantially right angular body whose forward end is provided with a toothed cutting bar cooperable with the upper side of said plates, and brackets carried by said mole head and including portions extending slidably through said slots to permit connection of reciprocatory operating means thereto.

3. An attachment for the loading end of a conveyor frame of the class described comprising a longitudinally elongated curved plate functioning as a guiding and excavating apron, said plate adapted to be fixedly mounted on the loading end of said frame, and being provided with a cutting edge and adjacent its opposite end with longitudinally elongated guide slots, a mole head mounted for reciprocation on said plates and comprising a substantially right angular body whose forward end is provided with a toothed cutting bar cooperable with the upper side of said plates, and brackets carried by said mole head and including portions extending slidably through said slots to permit connection of reciprocatory operating means thereto, said brackets being provided with anti friction rollers cooperable with the under side of the apron, and cover plates carried by said mole head and cooperable with said slots.

In testimony whereof I affix my signature.

WILLIAM MONROE HUFFMAN.
